L. B. WACKMAN

BARREL SEALING DEVICE

Filed March 12, 1921

FIG. 1.

FIG. 2.

FIG. 3.

Inventor:
Louis B. Wackman.

By H. G. Fletcher, Atty.

Patented Dec. 11, 1923.

1,476,935

UNITED STATES PATENT OFFICE.

LOUIS B. WACKMAN, OF ST. LOUIS, MISSOURI.

BARREL-SEALING DEVICE.

Application filed March 12, 1921. Serial No. 451,855.

To all whom it may concern:

Be it known that I, LOUIS B. WACKMAN, a citizen of the United States of America, and a resident of the city of St. Louis and 5 State of Missouri, have invented certain new and useful Improvements in a Barrel-Sealing Device, of which the following is a specification.

The primary object of this invention is to 10 provide an improved device for sealing the metallic lids or cover plates of metallic barrels.

Another object of the invention is to provide improved adjusting means for the sealing rollers of this improved device.

A further object of the invention is to provide the adjusting means of the expanding or sealing rollers with an improved adjustable limiting mechanism so that the 20 rollers cannot be moved too far outwardly in the expanding or sealing operation.

Other and further objects will appear in the specification and be specifically pointed out in the appended claims, reference being 25 had to the accompanying drawings exemplifying the invention, and in which,

Fig. 1 is a plan view of this improved device.

Fig. 2 is a longitudinal section taken on 30 the line II—II of Fig. 1.

Fig. 3 is a transverse section taken on the line III—III of Fig. 1.

With reference to the accompanying drawings, this improved device is comprised 35 of an approximately triangular shaped frame 1, and secured to the rear cross member 2 of said frame is a pair of expanding rollers 3, said rollers being spaced apart and arranged horizontally on the underside of 40 the frame by vertically arranged screws or pins 4.

Arranged centrally of the cross member 2 is the boss 5, said boss being threaded internally as designated at 6, and in engagement 45 with the threads 6 is the threaded portion 7 of the horizontally extending bar 8, said bar having a turning handle 9 secured at one end, the opposite end of said bar being turnably engaged within a sliding block 10 and secured to said block by the pin 11 which is carried by said block and engaged within the groove 12 of said bar 8. The block 10 is slidably mounted within a dove-tail guideway 13 which is formed in 55 the frame 1 in opposite disposition from

the boss 5, said block 10 having a horizontally arranged expanding roller 14 secured thereto on its underside by a holding screw 15.

Forming part of the frame 1 and arranged in alignment with the guideway 13 is a boss 16, said boss being threaded internally as designated at 17 and in engagement therewith is the threaded end 18 of the horizontally extending bar 19, said threaded end 18 bearing an adjustment nut 20 which is adapted to jam against the end of the boss 16.

As already related this improved device is for the purpose of expanding the closure 70 plates or lids of metallic barrels after they have been mounted in closing position to the barrel and in the operation thereof the device is mounted as shown in Figs. 1 and 2, onto the closure plate A, in which the expanding portion 21 of the rollers 3 and 14 will be engaged against the side wall B of the plate A, while the rollers themselves will rest on the depressed portion C of the plate A. If, however, the portions 21 of the 75 rollers do not engage the side wall B, the handle 9 of the bar 8 is turned in a right hand direction in which the block 10 bearing the roller 14 will be forced outwardly until the expanding portion 21 thereof will engage the wall B of the plate A and continued turning of the bar 8 will also force the expanding portions 21 of the rollers 3 80 against the wall B thereby placing the device ready for operation.

The bar 8 is then engaged by the operator at a position adjacent the handle 9 and at the same time the extending end of the bar 19 is engaged, one of said bars being pulled toward the operator while the other bar is 95 pushed away from the operator thereby presenting a horizontal turning movement to the frame 1 in which the rollers 3 and 14 will be forced to revolve against the wall B of the plate A, and during the turning of the 100 frame the handle 9 of the bar 8 is engaged and turned in a right hand direction thereby forcing the block 10, bearing the roller 14, outwardly and incidentally the pair of rollers 3 so that an under expanding groove 105 D will be eventually formed in the wall B of the plate A beneath the depending portion E of the barrel head.

So that the wall B of the plate A will not be expanded too far outwardly by the rollers 110

thereby creating a split or break in the side wall, the threaded end 18 of the bar 19 is adjusted to a position within the guideway 13 of the sliding block 10 so that the outward travel of said block will be limited on account of said block engaging the protruding threaded end of the bar 19, the adjusted position of the bar 19 being held by the nut 20.

After the sealing operation, it is obvious that the roller 14 is drawn inwardly by the manipulation of the bar 8 so that the frame holding the rollers can be removed from the plate A.

What I claim and desire to secure by U. S. Letters Patent is:

1. In a barrel sealing device, a frame having a series of expanding rollers, a sliding block carried by said frame supporting one of said rollers, means for adjusting said

block, and other adjustable means for limiting the travel of said block. 20

2. In a barrel sealing device, a frame having a series of spaced apart rollers, a sliding block carried by said frame for supporting one of said rollers, an adjusting bar secured at one end to said block, and adjustable means carried by said frame for limiting the travel of said block. 25

3. In a barrel sealing device, a frame having a pair of spaced apart rollers, a sliding block carried by said frame bearing an expanding roller, an adjusting bar secured at one end to said block for adjusting it away from or towards said pair of rollers, and a second bar turnably mounted in said frame 30 35 adapted to limit the travel of said block.

LOUIS B. WACKMAN.
